UNITED STATES PATENT OFFICE.

EFFINGER E. WHIPPLE, OF UTICA, NEW YORK.

SUPPORTING ATTACHMENT FOR HARROWS.

SPECIFICATION forming part of Letters Patent No. 611,160, dated September 20, 1898.

Application filed October 26, 1897. Serial No. 656,463. (No model.)

To all whom it may concern:

Be it known that I, EFFINGER E. WHIPPLE, a citizen of the United States, residing at Utica, in the county of Oneida and State of New York, have invented certain new and useful Improvements in Supporting Attachments for Harrows; and I do hereby declare the following to be a full, clear, and exact description of the invention, such as will enable others skilled in the art to which it appertains to make and use the same.

This invention relates to certain improvements in riding or supporting attachments for harrows or other soil-working implements.

The objects and nature of the invention will appear hereinafter; and the invention consists in certain novel features in construction and in arrangements and in combinations of parts, as more fully and particularly described and pointed out hereinafter.

Referring to the accompanying drawings, Figure 1 is a top plan view of a two-section lever-adjustment harrow provided with a construction illustrating an example of my invention. Fig. 2 is a side elevation thereof, the teeth being lowered, the rear portion of one harrow-section being partially broken away to show the supporting device. Fig. 3 is a view corresponding to Fig. 2, but showing the teeth elevated. Fig. 4 is a detail perspective of a form of the riding or supporting attachment which can be employed. Fig. 5 is a perspective of portions of the rear ends of the two harrow-sections and of the supporting or riding attachment. Fig. 6 is a detail view of a portion of the draft-tongue or stick of the attachment, showing adjustable loops for the standards from the harrow-frame and means whereby said loops can be tightened or loosened to prevent or permit lateral play of the standards. Fig. 7 shows a modification whereby loose connections or supports depend from the tongue to the harrow-frame and wherein the front end of the tongue can be spread or braced against lateral play.

In the drawings a two-section harrow of any desirable construction is shown. Each section is formed with its frame *a* and rocking tooth-bars *b*, carrying teeth *b'*. Each section has also lever adjusting or operating means for rocking the tooth-bars to raise and

lower the teeth. Any means can be provided for this purpose, the ordinary means being shown, comprising the upright lever *c*, rigid with a tooth-bar and carrying a locking-pawl engaging a segmental rack on the adjusting-bar, pivotally joined to standards from the remaining tooth-bars of the section. Those skilled in the art understand the operation of such a device. An evener-bar *d* can be arranged in front of both of the harrow-sections and independently coupled to each section loosely or otherwise, according to circumstances. The draft is attached to the evener-bar, although of course it is not necessary to my invention that the evener-bar be employed. Suitable supporting devices *e* can be provided for the front ends of the sections, such as depending shoes or rollers. The harrow-sections preferably are not directly coupled together in rear of the evener-bar, so that they can have certain free up-and-down play, although this is not essential to my invention.

The riding or supporting attachment comprises a draft-tongue or seat-stick *f*, arranged centrally of the two harrow-sections in the line of draft—that is, the stick is preferably arranged horizontally above the space between the two sections and extending from the front part of the harrow to the after part thereof. The tongue is usually formed of a straight stick or bar with an extension from its front end extended downwardly and loosely coupled to a forward part of the harrow. The drawings show the front end of the tongue coupled to the center portion of the evener-bar; but coupling to the evener-bar is not essential to the invention, as the front end of the tongue can be coupled at other points at the forward portion of the harrow. The rear end of the tongue is carried by a supporting-wheel *g*, which is usually located in rear of the center of the harrow, and the rear end of the tongue is preferably held elevated by plates or bars *g'*, secured rigidly to the tongue and depending therefrom, with the supporting-wheel mounted in and between them. The tongue carries a seat *f'*, usually arranged in rear of the vertical plane, including the axis of the supporting-wheel *g*, although this location is not essential to the invention. Nor is it essential to

the invention that the tongue carry a seat, although such is preferred practically.

Suitable means are provided to support or sustain the inner sides or portions of the harrow-sections at their after parts from said tongue, while the harrow-sections can be and are provided with supporting means at the after parts of their outer sides or portions—such as depending shoes *h* from the frame, 5 as shown in Fig. 2, or supporting-rollers *h'*, suitably mounted, as shown in other figures of the drawings—so that when the teeth of either or both harrow-sections are elevated the tongue will carry the after part of the inner side of a section, while the outer side and front supports carried by the sections will uphold the remainder of the weight of the frame and parts. Various means can be provided to partially support the inner sides of 10 the sections from the tongue when the teeth are elevated. For instance, the inner sides of the rear portions of the frames of the harrow-sections can be provided with rigid vertical standards *i*, preferably parallel and extending upwardly on opposite sides, respectively, of the tongue and to points above the same. The tongue is provided with rigid side loops or openings *i'*, through which said standards pass and reciprocate vertically 15 within certain bounds, and whereby the tongue is held against excessive lateral play. The loops can be formed to permit limited lateral tilting or play of the standards, if so desired, whereby the sections can rock laterally within certain bounds. The loops can be entirely rigid, as shown in Fig. 4, or can be formed of plates mounted and slidable in and out on parallel bolts rigid with the tongue and provided with adjusting-nuts at the outer 20 sides of the plates, as shown in Fig. 7, whereby the nuts can be turned up on the bolts to press the plates toward the standards and limit or prevent lateral play thereof independent of the tongue, or on loosening the nuts greater play of the standards and harrow-sections independent of the tongue is allowed. 25

Suitable means of various constructions can be provided to limit the downward movement of the standards, and consequently uphold 30 the harrow-sections when a certain distance below the tongue. For instance, the standards can be provided with series of transverse holes through which a pin *i*² can be passed above the loop of the tongue to form 35 a stop against further downward movement of the standard and permitting adjustment. The standard could be locked or limited in other ways. Also instead of the rigid standards loose connections, such as shown in 40 Fig. 7, could be employed. In this figure chains *j* are shown attached to the tongue and to the inner sides of the frames of the harrow-sections to uphold the same. The chains are formed of the proper length or 45 made capable of adjustment to permit independent upward movement of the sections

and yet limit their downward movement. Where such a loose supporting connection is employed, the front end of the tongue can be forked or braced and secured to the evener-bar or other part of the harrow at separated points to hold the tongue against excessive lateral play. 70

If it is desired to throw the weight of the riding or supporting attachment into the harrow, the standards can be secured to the tongue against the movement independently thereof, as by passing the stop-pins directly through the loops and standards. 75

I do not desire to limit myself to the exact arrangement of independent riding attachment shown nor to the location or method of attachment of the seat-stick or tongue *f* nor to any specific or particular means for supporting the rear end of said riding or supporting attachment. In a two-section harrow this arrangement of seat-stick has been found to be very effective; but it might be changed, and also the standards *i i* are not necessarily secured rigidly to the harrow-sections. 80 85 90

By means of my invention a very simple and effective and yet light-riding attachment is provided which is practically independent of the harrow—that is, the harrow has the proper or desired play independent 95 of the riding attachment, and the curved spring-teeth can be forced down and the harrow-frame elevated by the rider without leaving his seat—and also by employing a harrow with frame-supports carried by and moving 100 with the harrow while a portion of the frame is carried by the riding attachment many practical advantages are attained. 100

It is evident that various changes might be made in the forms, constructions, and arrangements of the parts described without departing from the spirit and scope of my invention. Hence I do not wish to limit the invention to exactly what is described and shown, but consider myself entitled to all 110 such changes as fall within the spirit and scope of the invention. 110

What I claim is—

1. A harrow having freely-movable sections, in combination with a wheeled support 115 extending over the space between the sections, the inner sides of the sections having standards extending up and loosely confined to said support and provided with means to limit the downward movement of the standards and sections independently of the support, substantially as described. 120

2. A two-section harrow, in combination with a tongue extended forwardly about centrally of the harrow and receiving its draft 125 from the harrow, plates secured to the rear portion of the tongue and depending therefrom, a supporting-wheel mounted between the plates, a seat mounted on the tongue, and independent supporting connections between 130 the tongue and inner portions of said sections, substantially as described.

3. A harrow, in combination with a wheeled support or riding attachment comprising a tongue extending forwardly over the harrow and connected with the draft thereof and at the after part of the harrow mounted on a wheel, said tongue having a vertical opening, and a standard rigid with the harrow and passing loosely up through said opening, and means to lock the standard to the tongue or limit its downward movement therethrough, substantially as described.

4. A harrow, in combination with a tongue extending forwardly over the harrow and connected with the draft thereof and at its rear mounted on a wheeled support at the after part of the harrow, said tongue held against excessive lateral play independent of the harrow, and a supporting connection between the tongue and after part of the harrow permitting upward movement of the harrow independent of the tongue but limiting the downward movement of the harrow, said harrow having front and rear frame-supports independent of said tongue, substantially as described.

5. A curved-spring-tooth lever-adjustment harrow having a certain rear portion provided with and carrying a depending ground-support, in combination with an independent wheeled riding attachment moving forward with the harrow and provided with a support limiting the downward movement of an opposite rear portion of the harrow whether the teeth are in or out of operative engagement with the soil, and a front frame-support, substantially as described.

6. A curved-spring-tooth lever-adjustment harrow having depending frame-supports at the front and outer side of the harrow carried by and moving with the same, in combination with an independent wheeled riding attachment moving forward with the harrow, and provided with a support for the opposite rear portion of the harrow limiting the downward movement thereof below a certain plane and permitting independent vertical play of the harrow with its frame-supports above said plane.

7. A two-section rocking-tooth-bar harrow having frame-supports at the front and rear outer portions of the sections carried by and moving with the frames and moving on the ground, in combination with a wheeled riding attachment moving with the harrow and provided with supports for the inner sides of the sections, substantially as described.

8. A lever-adjustment harrow having front and rear outer side supports traveling on the ground and carried by the harrow so that the weight thereof is on the harrow, in combination with an independent wheeled riding attachment arranged centrally of the harrow and loosely upholding the center thereof only, when in a certain plane and permitting independent movement above said plane with said front and outer rear side supports, thereby permitting the rider to raise and lower the

teeth of the harrow by the levers without leaving his seat on the riding attachment.

9. A rocking-tooth-bar lever-adjustment harrow having frame-supports, in combination with a tongue extending forwardly of the harrow and coupled at the front of the harrow to receive the draft therewith, a wheel-support at the after part of the harrow for the rear of said tongue, a seat carried by said tongue, a vertical standard confined to the frame of the harrow and loosely confined to said tongue to permit vertical reciprocation independently thereof, and a stop vertically adjustable on said standard to control the vertical movement of the standard independently of the tongue and consequently control the vertical movement of the harrow-frame independently of the tongue, substantially as described.

10. A several-section harrow, a front evener-bar to which the sections are coupled, and frame-supports carried by the sections, in combination with a tongue having a wheeled support at the after part of the harrow, said tongue extending forwardly centrally above the harrow with its front end forked or spread and confined to the evener-bar at separated points to hold the tongue against excessive lateral play, said tongue provided with depending supports attached to the section-frames and limiting the downward movement thereof below a certain plane and permitting limited lateral play of said sections independently of each other and the tongue, substantially as described.

11. A lever-adjustment harrow having frame-supports, in combination with an independent riding and supporting attachment consisting of a single tongue extending forwardly over the harrow and coupled with the draft thereof and at its rear provided with a depending frame provided with a wheeled support beneath the tongue, a depending support from an intermediate part of the tongue to the harrow-frame partially supporting the frame in a certain plane and permitting free independent vertical movement of the harrow and its attached parts above said plane, and a seat mounted on the tongue.

12. A several-section harrow, each section having supports depending from and attached to the front and outer sides of its frame, in combination with an independent riding and supporting wheeled attachment moving forward with the harrow and separate from said before-mentioned supports, said attachment provided with supports for the inner sides of said sections permitting play of said sections independent of the attachment and limiting the downward movement of the inner sides of said sections.

In testimony whereof I affix my signature in presence of two witnesses.
